UNITED STATES PATENT OFFICE

152,771

DESIGN FOR A TELEPHONE DIALING
IMPLEMENT

Horace F. Cutler, Malden, Mass.

Application February 17, 1948, Serial No. 144,544

Term of patent 14 years

(Cl. D26—14)

To all whom it may concern:

Be it known that I, Horace F. Cutler, a citizen of the United States, residing at Malden, in the county of Middlesex and State of Massachusetts, have invented a new, original, and ornamental Design for a Telephone Dialing Implement, of which the following is a specification, reference being had to the accompanying drawing, forming part thereof.

Figure 1 is a perspective view of a telephone dialing implement, showing my new design, and

Figure 2 is a cross-sectional view thereof, taken substantially in the plane of the line 2—2 of Figure 1.

I claim:

The ornamental design for a telephone dialing implement, as shown.

HORACE F. CUTLER.
